DEVICE FOR INTERNAL CALIPERING

Lucien Peras, Billancourt, France, assignor to Regie Nationale des Usines Renault, Billancourt, France, a French works

Application November 2, 1954, Serial No. 466,399

Claims priority, application France November 27, 1953

5 Claims. (Cl. 33—178)

Series trueing of internally revolving surfaces can only be effected with great precision on trueing machines equipped with devices allowing the operator constant control of the increase in internal diameter of the piece to be trued, or with a device which automatically stops the trueing cycle when the bore of the piece has reached the desired reading.

The devices hitherto proposed for this purpose generally comprise a lever the pivot point of which is attached to the frame of the machine, and which carries a diamond feeler maintained in contact with the bore to be trued. The variations in the radius of the latter react on the movements of the lever, said movements, amplified by an appropriate device, controlling for example the cycle of the machine. These known devices have certain disadvantages, especially that of a relatively low degree of precision, due to the fact that the comparative measurements are effected with reference to the frame of the machine. Thus are added all the sources of error arising from play in the machine, differences in the positions of successive pieces in the mandrel, etc.

The invention relates to a device for internal calipering for determining the diameter of a bore. According to the invention, measurement is effected with the help of two diametrically opposed contact feelers protruding from the external surface of a calipering barrel. The latter is split in such a way as to comprise two elements or portions, each carrying one contact feeler, and connected to one another by intermediate members of thin section, giving the barrel a certain elasticity in radial expansion and compression.

This deformability of the barrel allows it to be introduced into a bore having a diameter slightly smaller than the distance normally separating the contact surfaces of the feelers on the barrel in the non-deformed state, and an amplifying device indicates the difference between this diameter and the standard distance. When the device is used on a trueing machine, the development of the expansion of the calipering barrel during the finishing movements of the grindstone controls, for example, the working cycle of the machine.

Such a device ensures great precision of calipering, since measurement of the variations in diameter of the bore, which is more favorable than that of the variations in the radius, is virtually uninfluenced by vibration, the entire device being guided by the bore to be measured.

Two embodiments of devices according to the invention are described below by way of non-limitative examples and with reference to the attached drawing, wherein:

Fig. 1 is a perspective diagrammatic view of the operation of a calipering gauge;

Fig. 2 is a comparable view of a different embodiment.

In Fig. 1, the workpiece or body to be trued is designated by 1, and is being rotated in the direction of the arrow 2 by means of the mandrel (not shown) of a machine for trueing internally revolving surfaces. The grinding spindle 3, shown in the withdrawn position, causes the grindstone 4 to turn in the direction of the

2

arrow 5. The grinding spindle 3 also effects during the working cycle longitudinal reciprocal movements in accordance with the arrow 6 and a transverse movement in accordance with the arrow 7.

5 The calipering gauge comprises a support 8 of triangular form, pivoting about a bar 9, part of this support being formed as a jaw 10. The bearing plate 12 of the calipering barrel 13 is attached to this jaw by the screws 11. This barrel is split at 14, and, for a greater width, at 15. Two thin sections 16 and 17 are provided at the extremity of the barrel. The split 14 extends as far as the bearing plate 12 and the flange 12' of this bearing plate is connected to the member attached to the support 8 only by means of a member 18 of thin section. Two feelers 19 and 20, of diamond for example, are fitted in the walls of the two portions of 13a and 13b of the barrel, the contact surfaces of said feelers facing outwards.

Since the flange 12' is not attached to the support 8, it can easily be seen that the portion of the barrel carrying 20 the feeler 19 can bend resiliently about an axis 21, perpendicular to the general axis of the barrel, and about an axis parallel to the axis of the barrel and passing through the narrow section 18.

The flange 12' also carries a lever 22 acting in conjunction with a detecting device 23, attached to the support 8, and connected by the conduit 24 to an amplifying device (not shown), of known construction, a pneumatic amplifier for example.

30 The device functions as follows: The bore of the workpiece or body 1 having been trued up to within approximately 0.01 mm. of the reading to be obtained, the grinding spindle 3 withdraws in a conventional working cycle for the purpose of lining up the grindstone which thus leaves the bore. During this period when the grindstone is being lined up, the calipering gauge is placed in position between the workpiece or body 1 and the grindstone 4 by pivoting of the support 8 about the bar 9. The whole then occupies the position shown in Fig. 1.

40 The distance between the contact surfaces of the feelers 19 and 20 being adjusted to a reading of a few microns greater than that desired, the calipering barrel is introduced into the bore of the body or workpiece 1 by a slight compression of its normally cylindrical portion, the portion provided with a feeler 19 bending resiliently

45 about the axis 21 and the thin section 18. The grinding spindle 3 then advances towards the workpiece 1, the grindstone 4 enters the bore already containing the barrel, and effects therein, due to the existence of the wide split 15 in the barrel, the finishing movements, the spindle 3 simultaneously moving in the direction of the arrow 7.

50 The diameter of the bore increasing, and the feelers 19 and 20 remaining in contact with the wall of the workpiece, the expansion of the calipering barrel leads to a displacement of the lever 22, to which the detector 23 is sensitive. The operator of the machine can thus follow, by means of the amplifying device, the development of the diameter of the bore, and the amplifier can, for example, automatically control the stopping of the trueing cycle when the final reading is reached.

60 Fig. 2 shows a different embodiment of the internal calipering gauge according to the invention. The support 8 pivots about the bar 9 and carries the bearing plate 12 of the barrel 25, this latter being completely open at its two extremities and comprising two portions carrying the contact feelers 26 and 27, respectively. The portion of the barrel carrying the feeler 26 and comprising the flange 12' of the bearing plate can bend resiliently about the axis 28—29 passing through the grooves 30 and 31 forming thin sections allowing the calipering barrel to be compressed and to expand. The flange 12' of the bearing plate carries the adjustable feeler 32, the detector 23 being attached, via the bearing plate 12, to the support 8 and

connected by the conduit 24 to the amplifying device (not shown).

The devices described only represent particular embodiments, and it is quite evident that modifications may be made thereto, more particularly to adapt them to the types of pieces to be calipered, without going outside the scope of the invention.

I claim:

1. A device for caliper an internal cylindrical surface comprising, in combination, a support and a slotted barrel extending from one side thereof, said support being pivoted so that said barrel is adapted to be introduced into a workpiece having said internal cylindrical surface, said barrel having a central bore, said barrel comprising a first portion rigid with said support and a second portion free from connection with said support, and articulating means interconnecting the second portion with the rigid first portion to permit said portions to bend relatively to each other and a feeler carried by each portion at diametrically-opposite sides of said barrel for engagement with the cylindrical surface.

2. A device for caliper an internal cylindrical surface comprising, in combination, a support and a slotted barrel extending from one side thereof, said support being pivoted so that barrel is adapted to be introduced into a workpiece having said internal cylindrical surface, said barrel having a central bore, said barrel comprising a first portion rigid with said support and a second portion free from connection with said support, and articulating means interconnecting the second portion with the rigid first portion to permit said portions to bend relatively to each other, a feeler carried by each portion at diametrically-opposite sides of said barrel for engagement with the cylindrical surface, and detector means sensitive to the radial compression and expansion of the barrel as said portions bend about said articulation means in response to the contact of said feelers with the cylindrical surface.

3. A device for caliper an internal cylindrical surface comprising, in combination, a support and a slotted barrel extending from one side thereof, said support being pivoted so that said barrel is adapted to be introduced into a workpiece having said internal cylindrical surface, said barrel having a central bore, said barrel comprising a first portion rigid with said support and a second portion free from connection with said support, and articulating means along two mutually perpendicular axes interconnecting the second portion with the rigid first portion to permit said

portions to bend relatively to each other, and a feeler carried by each portion at diametrically-opposite sides of said barrel for engagement with the cylindrical surface.

4. A device for caliper an internal cylindrical surface comprising, in combination, a support and a slotted barrel extending from one side thereof, said support being pivoted so that said barrel is adapted to be introduced into a workpiece having said internal cylindrical surface, said barrel having a central bore, said barrel being formed from a single integral body comprising a first portion rigid with said support and a second portion free from connection with said support, and articulating means interconnecting the second portion with the rigid first portion to permit said portions to bend relatively to each other, and a feeler carried by each portion at diametrically-opposite sides of said barrel for engagement with the cylindrical surface.

5. A device for caliper an internal cylindrical surface comprising, in combination, a support and a slotted barrel extending from one side thereof, said support being pivoted so that said barrel is adapted to be introduced into a workpiece having said internal cylindrical surface, said barrel having a central bore, said barrel being formed from a single integral body comprising a first portion rigid with said support, and articulating means interconnecting the second portion with the rigid first portion to permit said portions to bend relatively to each other, said articulating means being defined by portions of reduced thickness in said barrel body between said portions, and a feeler carried by each portion at diametrically-opposite sides of said barrel for engagement with the cylindrical surface.
